United States Patent Office

Des. 212,928
Patented Dec. 10, 1968

212,928

PILLOWCASE OR SIMILAR ARTICLE OF BED LINEN

Nancy Ann Scherer, Plainfield, N.J., assignor to Cannon
Mills Company, Kannapolis, N.C., a corporation of North Carolina

Filed Oct. 20, 1967, Ser. No. 9,078

Term of patent 14 years

(Cl. D92—26)

FIGURE 1 is a plan view of a pillowcase showing my new design, the side opposite thereto being substantially identical; and

I claim:

The ornamental design for a pillowcase or similar article of bed linen, substantially as shown and described.
